UNITED STATES PATENT OFFICE.

WILLIAM N. BEST, OF BROOKLYN, NEW YORK.

TRUSS.

1,221,016.

Specification of Letters Patent.

Patented Apr. 3, 1917.

Application filed June 28, 1916. Serial No. 106,326.

To all whom it may concern:

Be it known that I, WILLIAM N. BEST, a citizen of the United States, and resident of New York, borough of Brooklyn, in the county of Kings and State of New York, have invented certain new and useful Improvements in Trusses, of which the following is a specification.

This invention relates to certain improvements in trusses and has for its main object to permit the pad to be held firmly in place but at the same time to permit of a relative movement of the parts of the pad, or an outward movement of the entire operating 15 surface of the pad to accommodate the same to movements of the body and to insure its proper operation at all times.

As an important feature of my improved construction, I form the pad of two main 20 sections, one of which is connected to the support and the other of which presents the pressure or operating face, and so connect these parts that the pressure face may move outwardly either in parallelism or with a 25 tilting movement.

Reference is to be had to the accompanying drawings illustrating certain embodiments of my invention and in which similar 30 reference characters indicate corresponding parts in the several views. In these drawings,

Fig. 1 is an outer face view,

Fig. 2 is a section on the line 2—2 of Fig. 1.

Fig. 3 is a view somewhat similar to Fig. 2, but showing the two parts separated and the springs removed, and

Figs. 4 and 5 are details showing other arrangements of mounting and supporting 40 the springs.

In the specific construction illustrated in Figs. 1, 2 and 3, the pad or body portion of the truss includes two main sections 10 and 11. These may be made of hard rubber, 45 stamped metal, or any other suitable material and may be covered or coated to present the desired character of surface. Each part is substantially cup-shaped and the two are 50 so designed that the open end of one may telescope within the open end of the other to form a central chamber or cavity 12.

The part 10 may have its operating face 55 curved in accordance with the curvature of the portion of the body with which it is to engage while the part 11 may have any suitable means for permitting of its attach-

ment to a suitable support. If this support be in the form of a belt as is common in certain forms of trusses, the top part 11 may have a pair of transverse bars 14 rigidly secured thereto and extending substantially parallel to each other and diagonally of the top. These may be spaced a short distance through said wall and secured by nuts or in any other suitable manner. These permit of 60 the attachment of the truss to a belt indicated in dotted lines in Fig. 1.

Within the chamber 12 is mounted one or more springs normally tending to press the two parts away from each other to the limiting distance. In the construction shown in Figs. 2 and 3, the inner surfaces of the top and bottom walls are provided with projections 15 which may extend within and act as supports for coil springs 16. These are 70 of such strength that they are compressed but little when the truss is firmly secured in the desired position on the body.

Instead of holding the springs against lateral movement at their ends by projections 15, as shown in Figs. 2 and 3, I may provide annular flanges 17, as shown in Fig. 4, and which present sockets or recesses 18 into which the ends of the springs may seat. It is not essential that coil springs be employed as I may employ leaf springs as shown in Fig. 5. In this construction, I employ two leaf springs 19 and 20 extending substantially at right angles to each other. Each spring may be bowed so that its center 80 portion engages with the inner surface of the part 10 while its ends may engage with the inner surface of the part 11. The terminal portions of the springs may extend down along the side walls of the part 11 so 85 as to prevent any endwise movement of the springs if desired.

The two parts telescope with sufficient lost motion or free play at the engaging surfaces so that the two parts may be moved 100 toward or from each other in parallelism or the part 10 may tilt or swing with a greater compression of the spring or springs adjacent to one end than adjacent to the other. This permits the operating part 10 to adjust 105 itself to the position of the body during the movement of the latter in walking, sitting or bending over.

To limit the separating movement of the two parts, I preferably provide the side 110 walls of the inner part 11 with longitudinally extending slots 21 and provide the side

walls of the outer part 10 with pins 22 extending inwardly into these slots. The pins may have threaded portions engaging in the wall of the part 10 so as to be normally retained in proper position but capable of ready removal if desired. There may be any desired number of these lost motion connections, but I find that four is sufficient if spaced equal distances apart around the periphery.

To prevent moisture or any solid matter from gaining access to the chamber 12 and to prevent any part of the body from being caught or pinched between the relatively movable parts, I preferably provide a flexible connecting band 23. This extends around the pad and has one edge connected to one part and the opposite edge to the other part. The band is sufficiently wide and is connected along lines spaced a sufficient distance from the edges of the parts to permit the desired telescoping movement. The band may be of cloth, rubber or other desired flexible fabric, although it is preferably substantially water-proof and of such character that it will not be injured by washing the entire device.

Having thus described my invention, what I claim as new and desire to secure by Letters Patent is:

A truss including two cup-shaped members having peripheral walls arranged to telescope one within the other and encircling a central chamber, one of said members constituting a base and the other presenting a bearing surface, the peripheral walls of said members having interengaging parts for limiting the movement of said members toward and from each other and the inner peripheral wall being curved inwardly at its free edge to permit a relative tilting of one member in respect to the other, a belt guide carried by and disposed substantially parallel to the said base, a sealing strip secured to each of said members along the free edge of the peripheral wall of the outer member and a plurality of springs within said chamber and tending to separate said members to the limiting extent.

Signed at New York, in the county of New York and State of New York this 26th day of June A. D. 1916.

WILLIAM N. BEST.
